UNITED STATES PATENT OFFICE.

FRED I. RAYMOND, OF EVANSTON, ILLINOIS, ASSIGNOR TO RAYMOND BROTHERS IMPACT PULVERIZER COMPANY, OF CHICAGO, ILLINOIS, A CORPORATION OF ILLINOIS.

PULVERIZING APPARATUS.

Application filed August 16, 1920. Serial No. 403,756.

To all whom it may concern:

Be it known that I, FRED I. RAYMOND, a citizen of the United States, residing at Evanston, in the county of Cook and State 5 of Illinois, have invented certain new and useful Improvements in Pulverizing Apparatus, of which the following is a specification.

My invention relates to pulverizing apparatus and more particularly to the type of apparatus in which the pulverized material is withdrawn from the pulverizer or grinding mill by a current of air, separated and the coarser material returned for further 15 pulverization.

In pulverizing apparatus of this type, a current of air is passed through the pulverizer casing and the material which is sufficiently fine to be capable of suspension in 20 the current of air is thus withdrawn from the pulverizer. The material is then passed into a separator capable of effecting a separation of the finer particles of material from those which are not sufficiently fine, and 25 which may be called tailings. The coarser particles or tailings are then returned to the pulverizer for further pulverization. It has been customary to introduce the tailings into the pulverizer at a point where they must 30 travel against the outgoing current of air to reach the pulverizing mechanism. The result has been that a large percentage of the tailings are carried off again in the current of air without reaching the pulverizing 35 mechanism. This greatly reduces the efficiency of the pulverizer because eventually the air current becomes burdened with a large percentage of material which is fine enough to be suspended in the air and yet 40 not sufficiently fine to be removed by the separator as the finer product.

The object of the present invention is to provide certain novel and improved constructions in pulverizing apparatus where- 45 by the coarser particles of material are effectively repulverized and the efficiency or capacity of pulverizing apparatus of this type is increased.

The invention is illustrated in a certain 50 preferred embodiment in the accompanying drawings in which:

Fig. 1 is an elevation of a pulverizing apparatus to which my invention has been applied.

Fig. 2 is an elevation partly in section of 55 the pulverizer and separator.

Fig. 3 is an elevation of the pulverizer and separator of Fig. 2 taken from the right hand of the structure as shown in Fig. 2, and having a portion of the outer casing 60 broken away.

Like characters of reference designate like parts in the several figures of the drawings.

In Fig. 1 of the drawings I have illustrated a pulverizing apparatus of a well 65 known type which comprises in general a pulverizer 10, a separator 11, a fan or blower 12, a cyclone collector 13 and a collecting bin 14. The pulverizer is supplied with crushed material from the feed bin 15 70 through a feed spout 16 and a feeding mechanism 17, the particular construction of which forms no part of this invention.

The pulverizer 10 is of a well known type and comprises a casing 18 having a semi- 75 cylindrical lower portion 19 in which the pulverizing element revolves. The pulverizing element consists of a rotary beater 20 mounted on a shaft 21 supported by bearings 22 and rotated by a pulley 23 at a rate suffi- 80 cient to effect pulverization of the material. The general construction of the pulverizer forms no part of this invention.

The separator 11 is supported above the casing 18 and comprises an outer shell 24 85 and an inner shell or cone 25, the space between the outer and inner shells communicating with the pulverizer casing.

The fan or blower 12 is supported in a convenient position above the top of the separator by a platform 26 on supports 27 and connected on its intake or suction side with the inner shell 25 of the separator by means of the pipe 28. The pressure side of the fan 12 is connected with the cyclone collector 95 13 by the pipe 29.

The air outlet of the cyclone collector is connected with the pulverizing mill casing by means of a pipe or conduit 30, for the purpose hereinafter noted.

The pipe 30 terminates at 31 at a point in close proximity to the blades of the revolving beater 20. The lower part of the inner shell 25 is connected with the terminal of the pipe 30 by means of a conduit 32 in which is 105 positioned a rotary valve 33 adapted to permit the passage of material from the cone 25 into the conduit 32 and yet at the same

time preventing the passage of a current of air through the conduit.

Operation: The apparatus operates as follows:

5 The material to be pulverized is fed into the pulverizer casing above the rotary beater by means of a suitable feeding device which may be adjusted to feed the material at any desired rate. The material falls by gravity 10 onto the grinding element which in the form of apparatus illustrated is a rotary beater revolving in a clockwise direction as indicated by the arrow in Fig. 2.

The suction fan 12 induces a rising current of air as indicated by the arrows in Fig. 2 through the pulverizer casing 18 and the space between the outer and inner shells 24 and 25 and through the openings 34 in the upper part of the inner cone 25 and directed in a tangential path so as to set up a whirling motion. After the material has been pulverized sufficiently fine to be suspended in the rising current of air it is carried into the separator and there a separation is effected between the particles of product which have been pulverized sufficiently fine and those which have not been pulverized sufficiently fine. The coarser particles or tailings are permitted to fall to the 30 bottom of the inner cone 25. The general construction and operation of the separator is illustrated in the patent to Pool 870,383 and accordingly need not be further described inasmuch as its specific construction 35 forms no part of this invention.

The finer particles of product are carried out of the separator 11 through the pipe 28 the blower 12, and the pipe 29 and are introduced tangentially into the cyclone collector 13 where the solid particles are separated from the air, and the former permitted to collect in the bin 14. Inasmuch as the cyclone collector is not 100 per cent efficient the outgoing air from the cyclone collector 40 usually carries a certain percentage of fine particles suspended therein. It is accordingly customary to return such air to the pulverizer casing in order both to save the product and to prevent the escape of the dust 45 into the atmosphere. This air issues into the casing 18 at a point sufficiently close to the rotary beater 20 so as to be drawn through the beater before it again ascends through the casing. A valve 35 is provided for controlling circulation of the air. The system 50 is closed except for the opening through the pipe 36 which is located at a point where the pressure in the system is substantially atmospheric and which serves to balance the 55 system and permit the escape of excess air from the system. If desired a bag collector is placed over the end of the pipe 36 so as to prevent the escape of dust into the air.

The coarser particles of material collected 60 in the cone 25 which are not sufficiently fine

to be considered finished product are permitted to fall through the conduit 32 out of contact with the rising current of air to the point of entry of the return air through the pipe 30. This construction insures the 70 passage of the coarser particles through the pulverizer for further pulverization. The valve 33 which is rotated at a suitable speed by the pulley 37 permits the escape of these particles from the inner cone 25 without 75 permitting any current of air to be set up through the cone 25 and the conduit 32 by the suction of the blower.

In former pulverizing apparatus of this type it is customary to permit the coarser 80 particles to fall into the pulverizer casing from the bottom of the cone 25 as illustrated in the Poole patent. A large percentage of such coarser particles never reach the pulverizing element because they have already 85 been pulverized sufficiently fine to be suspended in the rising current of air and accordingly are carried out of the pulverizer with the current of air passing between the outer and inner shells 24 and 25. 90

With the present construction the coarser particles are returned directly to the pulverizing element out of contact with the rising current of air and are drawn into the pulverizing element along with the 95 return air from the pipe 30.

It should be noted that my invention is limited to a specific construction of pulverizer or to a separator which operates by the action of centrifugal force as in the 100 separator illustrated. It is applicable to pulverizing apparatus in which the pulverized material is withdrawn by a current of air and an accurate separation of the material so withdrawn effected between the finer 105 product and the coarser product.

In the claims the term air is employed to designate the medium carrying the pulverized material in suspension but it will be understood that this term is used merely 110 for the sake of brevity instead of the more generic term "gaseous medium" or its equivalent.

I claim:

1. A pulverizing apparatus comprising a 115 casing, a pulverizing element in said casing, a separator, a fan for drawing a stream of air and pulverized material from said casing through said separator, a conduit leading from said separator towards said pulverizing element and located within the suctional influence of said fan, and means in said conduit adapted to permit the coarser material to pass from the separator to the pulverizing element but adapted to prevent 120 passage of a current of air in the reverse direction through the conduit. 125

2. In pulverizing apparatus, the combination of a pulverizer comprising a casing having a pulverizing element therein, a sepa-

rator associated with said pulverizer and comprising an outer cone and an inner cone, a suction fan connected with said inner cone and adapted to induce a current of air from 5 said pulverizer into said separator between said cones, and means in said inner cone for directing the incoming air in tangential paths, said separator being adapted to effect a separation between the fine and the coarse material, a collector connected with 10 said separator for collecting the fine material, and a conduit connected with said inner cone provided with means for returning the coarse material to said pulverizing element out of contact with said induced current of air. 15

FRED I. RAYMOND.
